UNITED STATES PATENT OFFICE.

JAMES J. CARMICHAEL, OF RIDGWAY, COLORADO.

AUTOMATIC CYLINDER-COCK.

1,395,796.

Specification of Letters Patent.

Patented Nov. 1, 1921.

Application filed January 28, 1916. Serial No. 74,909.

To all whom it may concern:

Be it known that I, JAMES J. CARMICHAEL, a citizen of the United States, residing at Ridgway, in the county of Ouray and State 5 of Colorado, have invented certain new and useful Improvements in Automatic Cylinder-Cocks; and I do hereby declare the following to be a full, clear, and exact description of the invention, such as will enable others 10 skilled in the art to which it appertains to make and use the same.

The invention relates to improvements in cylinder cocks.

The object of the present invention is to 15 improve the construction of cylinder cocks and to provide an automatic cylinder cock controlled by the steam pressure in the cylinder and adapted to provide an open cylinder cock in advance of the piston head at all 20 times whereby water is conveyed away from the cylinder and is prevented from entering the smoke box and the stack or causing the breaking of packing ring and cylinder heads.

A further object of the invention is to 25 provide an automatic cylinder cock of this character which will enable the discharged water and steam to be conveyed either to a point centrally between the rails at any point beneath the engine or to the ash pan so that 30 the steam may pass upward through the grate and flues to the stack.

A further object of the invention is to 35 provide automatic cylinder cocks of this character capable of ready adjustment to regulate the valve travel and adapted to be operated by a relatively small valve travel so that there will be comparatively little 40 wear on the valve of the automatic cylinder cock.

With these and other objects in view the 45 invention consists in the construction and novel combination and arrangement of parts hereinafter fully described, illustrated in the accompanying drawings and pointed out in the claims hereto appended, it being understood that various changes in the form, proportion and minor details of construction 50 may be resorted to without departing from the spirit or sacrificing any of the advantages of the invention.

In the drawing—

Figure 1 is a longitudinal sectional view 55 of a cylinder provided with automatic cylinder cocks constructed in accordance with this invention,

Fig. 2 is a detail view of the pipes for

conveying away the discharge water and steam,

Fig. 3 is a detail view showing an adjustment for regulating the valve travel of the 60 cylinder cock.

Like numerals of reference designate corresponding parts in the several figures of the drawing.

In the accompanying drawing in which 65 is illustrated the preferred embodiment of the invention, 1 designates a locomotive cylinder of the usual construction having a steam chest 2 at the top for a slide valve 3 which controls the admission and exhaust of 70 steam to and from the cylinder 1 in the usual manner through ports 4 and 5 and while an inside slide valve is shown an outside or piston valve may of course be employed.

The cylinder is equipped at the bottom 75 with automatic cylinder cocks consisting of suitable casings 7 connected at the top to and depending from the bottom of the cylinder 1 at openings or ports 8 thereof. The casings of the automatic cylinder cocks are 80 provided with horizontally aligned seats 9 for check valves 10 mounted on valve stems 11 and 12 which are adjustably connected at their ends at a point intermediate of the ends of the cylinder. Any suitable means 85 may of course be employed for adjustably connecting the valve stems and in the accompanying drawing is shown one form of connection in which one of the valve stems is provided with a tubular portion 12 in- 90 teriorly threaded to receive a threaded portion 11 of the other valve stem, which is adapted to be screwed into and out of the tubular portion 12 and which is locked in its adjustment by a nut 13 mounted on the 95 threaded portion 11 and engaging the adjacent end of the tubular portion 12. The casings of the cylinder cocks are connected at the bottom or lower end with a pipe 15 having a branch 16 extending inwardly 100 transversely of the locomotive to a point between the rails so as to discharge steam thereat to prevent the discharged steam from obscuring train men and signals and frightening horses and the like. The branch 105 pipe 16 may lead back to the ash pan so that the steam will pass upward through the grate and through the flues to the smoke stack. When steam is admitted to one end of the cylinder for moving the piston head 110 17 to the other end of the cylinder the steam pressure acting on the check valve of the

cylinder cock at the end at which the steam is admitted will close such check valve and automatically open the other check valve through the action of the valve stems which 5 when moved in one direction opens one of the check valves and closes the other and when moved in the opposite direction reverses the position of the check valves. The check valves of the cylinder cocks in practice are designed to have three sixteenths of an inch travel so that there will be comparatively little wear on the valves owing to the small amount of movement in opening and closing the same. By positively conducting the water from the cylinder at the bottom thereof, foaming and injury to the parts are effectually prevented.

What is claimed is:—

1. A cylinder cock including a pair of 20 casings depending from a steam cylinder at opposite sides of the piston thereof, said casings having valve seats therein in close proximity to said cylinder and packing glands located at their inner sides, valves 25 located in the casing for engaging said valve seats and having stems passing through the glands and adjustably connected, and a discharge pipe connected to said casings.
2. A cylinder cock including a pair of 30 vertically arranged casings having their upper ends connected directly to the under side of a steam cylinder adjacent the ends thereof and provided intermediate their ends with

vertical valve seats facing each other, valves 35 within the casings, stems carried by the valves and extending laterally beyond the casings in the direction of each other, means adjustably connecting the valve stems together and located exteriorly of said casings, and a drain pipe located beyond said stems 40 and means and connected to the lower ends of the casings.

3. A cylinder cock including a pair of vertically arranged casings having their upper ends threaded directly into the under 45 side of a steam cylinder adjacent the ends thereof and provided intermediate their ends with vertical valve seats facing each other, valves within the casings, stems carried by the valves and extending laterally from the 50 casings in the direction of each other, means located externally of the casings adjustably connecting the valve stems to permit the stroke of the valves to be increased or decreased, to permit both valves to be moved 55 onto their seats and turned with respect thereto, and a drain pipe located beyond said stems and means and connected to the lower ends of the casings.

In testimony whereof I affix my signature 60 in presence of two witnesses.

JAMES J. CARMICHAEL.
